United States Patent Office.

ANDREAS VANG, OF CHICAGO, ILLINOIS.

Letters Patent No. 72,180, dated December 10, 1867.

IMPROVEMENT IN WATER-INDICATORS FOR BOILERS.

The Schedule referred to in these Letters Patent and making part of the same.

TO ALL WHOM IT MAY CONCERN:

Be it known that I, ANDREAS VANG, of Chicago, in the county of Cook, and State of Illinois, have invented a new and useful Machine to Gauge the Water in Steam-Boilers; and I do hereby declare that the following is a full and exact description thereof, reference being had to the accompanying drawings, and the letters of reference marked thereon, making a part of this specification.

The object of my invention is to indicate at all times the height of the water in any steam-boiler to which my invention may be applied, to the eye by an indicator, and also to the ear by a steam-whistle, by means of a hollow water-tight metallic globe, of convenient size, resting upon the surface of the water in the boiler, and connected by an arm, running parallel with the head of the boiler to a cylinder provided with a steam-valve opening to the steam-whistle, as it revolves by the raising or lowering of the water in the boiler, in a tube running through the head of the boiler, and to which tube the dial of the indicator and the steam-whistle are fastened; and as the globe rises or falls, by the rising or lowering of the water in the boiler, the height of the water is indicated upon the face of the dial by a hand attached to the outer end of the cylinder, or, should the water sink below a certain point, by the opening of the steam-valve to the whistle, and sounding the same as a warning of danger.

To enable others skilled in the art to make and use my invention, I will proceed to describe its construction and operation.

I construct the globe *a* of copper, or any other suitable metal, about an eighth of an inch in thickness, and five to six inches in diameter, water-tight, and it may be lined inside or filled with cork, and attach the same by an arm, *b*, to a cylinder, *c*, providing the cylinder with a steam-valve, *d*, to which cylinder I adjust a tube, *e e*, which is to be inserted into the boiler-head, and made fast by a nut, within which the cylinder revolves, and upon the outer end of which is adjusted an indicator, *f*, and in which a steam-whistle is placed, in a position corresponding with the position of the valve *d*. My invention may be applied to any steam-boiler, and is to be adjusted so that the globe *a* rests upon the surface of the water in the boiler at its proper height; and as the water is increased or diminished in the boiler, the globe will rise or fall correspondingly, the height of the water, therefore, being shown by the indicator *f* at all times; and should the water at any time increase or diminish above or below a certain point, the steam-valve is opened to the whistle, which is thereby sounded as an additional indication of the stage of the water in the boiler, and as a warning of danger.

What I claim as my invention, and desire to secure by Letters Patent, is—

The arrangement of the globe *a*, arm *b*, cylinder *c*, indicator *f*, and whistle *g*, substantially as herein set forth.

A. VANG.
